UNITED STATES PATENT OFFICE.

RICHARD M. HOPKINS, OF NEW YORK, N. Y., ASSIGNOR TO THE AMERICAN DISTRICT TELEGRAPH COMPANY, A CORPORATION OF NEW JERSEY.

ELECTRIC SIGNALING SYSTEM.

1,075,421.

Specification of Letters Patent. Patented Oct. 14, 1913.

Application filed January 27, 1913. Serial No. 744,325.

To all whom it may concern:

Be it known that I, RICHARD M. HOPKINS, citizen of the United States, residing in the borough of Bronx of the city of New York, in the county of New York, in the State of New York, have invented certain new and useful Improvements in Electric Signaling Systems, of which the following is a specification, reference being had to the accompanying drawings, which form a part hereof.

This invention relates to electric signaling systems. It is adapted for various uses but was especially designed and is particularly adapted for use as a fire alarm system. In systems of this character, it has been the practice heretofore to arrange one or more alarm instruments, such as gongs, and one or more switch instruments or signal transmitters in series with a common source of current supply and in a normally closed circuit. The current required to operate such a system is considerable and inasmuch as the circuit is normally closed and ordinarily operates at long intervals for periods of short duration, there is a great waste of current energy during the time that the alarm or signal instruments are not in actual operation.

The present invention seeks primarily, to provide a reliable and efficient system which shall effect a great saving in current consumption. This is accomplished by maintaining in the normally closed signal circuit a current of minimum strength and then increasing the current sufficiently to operate the signal instrument or instruments in the circuit at such time as it is desired that the signal instrument or instruments shall be in active operation.

Associated with the signal circuit is a test signal designed to operate when any derangement of the signal system occurs, such as a break at any part of the circuit or failure of current therein, and thereby serving as a test of the efficiency or working condition of the system.

In the accompanying drawings forming part of this specification, and in which like reference numerals designate corresponding parts, Figure 1 is a diagram of the system in its preferred form. Fig. 2 is an end elevation of one of the relays employed in the system. Fig. 3 is a diagram of the invention in modified arrangement.

Referring now to the invention as shown in Fig. 1, 1 is an electric signal instrument which may be of any suitable design, but is here shown as a gong.

2 is a switch instrument or signal transmitter and may be of any suitable design. It operates the circuit controller 3 and is here shown in a form well known in the art.

4 is a low resistance magnet.

5 is a high resistance magnet and 6 is a resistance device.

The signal instrument 1, circuit controller 3, magnets 4 and 5, and resistance 6 are all arranged in series with battery 7 and in a normally closed signal circuit. This circuit may be traced as follows:—from battery 7, through wire 8, binding post 9, wire 10, magnet 4, wire 11, binding post 12, wire 13, magnet 14 of the signal instrument 1, wire 15, circuit controller 3, wire 16, binding post 17, wire 18, magnet 5, wire 19, resistance 6, wire 20, binding post 21, and wire 22 back to battery 7. Magnet 5 is wound to a high resistance, say about 2,000 ohms, and magnet 4 is wound to a low resistance, say about 12 ohms. The resistance 6 is increased in accordance with the increase in the number of signal instruments that may be included in the signal circuit. In the drawing, the resistance 6 includes two resistance tubes, only one signal instrument being shown in the signal circuit. The signal circuit, as described, normally carries a relatively small current because of the high resistance due to magnet 5 and resistance 6. That portion of the circuit extending from binding post 17 through wire 18, magnet 5, wire 19, resistance 6 and wire 20 to clip 38 may be termed a high resistance circuit-portion because in this portion of the signal circuit is included the resistance which is responsible for the small current normally carried by the signal circuit. It will be understood, of course, that most of the resistance required in this circuit-portion may be included in magnet 5 alone or in resistance tubes alone, or the resistance may be distributed between these two devices, or otherwise provided in this circuit-portion.

The signal instrument 1 is of such character that it is responsive to a relatively large current only. In this signal instrument, as shown in the drawings, the magnet 14 operates armature 23 which vibrates between stops 24 and 25, and is normally retracted. The signal instrument 1 is of such character that it is responsive to a relatively large current only. In this signal instrument, as shown in the drawings, the magnet 14 operates armature 23 which vibrates between stops 24 and 25, and is normally retracted.

by spring 26 against stop 25. On the upper end of the armature is mounted a spring 27 which carries a bell tapper 28 arranged to strike the gong 29 by bending spring 27 after the armature has been arrested by that one of its stops nearest the gong.

The signal transmitter 2, as shown, is of the usual type. It includes the circuit controller 3 which has a finger 30 on one of its springs designed to be operated to make and break the signal circuit by the teeth on the signal wheel 31. The signal wheel 31 is operated by the usual spring actuated gearing 32 which need not be described. 10 When the lever 33, connected with this gearing, is depressed, the spring is wound up. When the lever is released the gearing rotates the signal wheel 31 counter-clockwise, the teeth on the wheel 31 acting upon finger 30 to make and break the signal circuit such number of times and at such spaced intervals as is determined by the number and position of the teeth on the signal wheel. The signal instrument is arranged to respond in 15 accordance with this operation of circuit controller 3 by the signal wheel. In the present instance, the signal wheel 31 has its teeth so arranged as to transmit to the signal instrument through the circuit controller 3, 20 the number 123 which number is the designation of the particular station to which the signal transmitter pertains. There may be as many signal transmitters and as many signal instruments connected in the circuit 25 30 to make and break the signal circuit such number of times and at such spaced intervals as is determined by the number and position of the teeth on the signal wheel. The signal instrument is arranged to respond in accordance with this operation of circuit controller 3 by the signal wheel. In the present instance, the signal wheel 31 has its teeth so arranged as to transmit to the signal instrument through the circuit controller 3, 35 the number 123 which number is the designation of the particular station to which the signal transmitter pertains. There may be as many signal transmitters and as many signal instruments connected in the circuit 40 45 as the requirements of the service demand. These would ordinarily be placed at different localities, such as different parts of a building or buildings. It will be seen that, although the circuit is shown as closed, magnet 14 is unresponsive to the current, the armature 23 resting against the stop 25. This is due to the fact that the current in the circuit is greatly reduced, below that required to make magnet 14 respond, by the high resistance circuit-portion which is normally included in the signal circuit. When the current in the circuit is raised to the requisite value, magnet 14 responds and pulls over its armature against stop 24. 50 When, thereafter, the current in the circuit is reduced to normal, the armature flies back against stop 23, spring 27 bending to permit the tapper 28 to strike the gong 29 one beat. The manner in which the gong operates to sound the required signal number in response to the electric impulses produced by the signal transmitter will be explained hereinafter.

Extending around the high resistance circuit-portion, heretofore described, is an auxiliary circuit member extending from the binding post 17, through wire 34, contact 35, armature 36 of magnet 5, wire 37 which is connected to and moves with the armature, clip 38, to wire 20. This auxil-

lary circuit member is normally open at contact 35, the break being controlled by armature 36. When armature 36 drops to close this circuit member, the high resistance circuit-portion is shunted out of the signal circuit, the auxiliary circuit member then included in the signal circuit being of much lower resistance. This increases the current in the signal circuit to the requisite value to make the gong magnet 14 respond when the circuit is next closed at circuit controller 3. 70 Armature 36 and contact 35 may be termed a current changer inasmuch as they operate, when closed, to increase the current and, when separated, to diminish the current 75 which may flow in the signal circuit. The auxiliary circuit member thus traced through armature 36, from contact post 17 to wire 20 may be termed a current-increasing circuit member, inasmuch as this circuit 80 member, when included in the signal circuit, operates to increase the current in the signal circuit. Magnet 5 exercises its control over the current-increasing circuit member when it releases armature 36. 85

In the normal condition of the circuit, magnet 5 acts to hold up its armature so as to maintain the break in the current-increasing member at contact 35. After armature 36 has been released, it is moved back or 90 restored to normal position by the operation of magnet 4. This magnet, which may be termed the restoring magnet, may be made to operate in any suitable manner to restore armature 36 to normal position. As shown 95 in the drawings, its action upon this armature is mechanical. It is provided with projecting pole pieces 39 which pass through holes in the armature 40. The armature is provided with a finger 41 adapted to move 100 against armature 36 and restore it to normal position when its own armature 40 is attracted by magnet 4. Armature 40 is held normally retracted by spring 42 attached to the adjusting screw 43. 105

44 is an adjustable stop to regulate the throw of armature 40 and its finger 41. Restoring magnet 4 is relatively slow acting, being so designed to permit the armature 23 of signal instrument 1 to be attracted before 110 magnet 4 lifts armature 36.

Associated with the signal circuit and controlled by it is a test signal 45, here shown in the form of an electric bell whose purpose is to test the normal condition or 115 operativeness of the signal circuit. This test signal is operated by a circuit extending from battery 46, through wire 22, contact post 21, wire 20, clip 38, wire 37, armature 36, contact 47, wire 48, signal 45, back 120 to battery. When armature 36 is held up by magnet 5, the circuit of this test signal is broken at contact 47. If any derangement of the system occurs, such as a break 125 at any part of the signal circuit or a failure 130

of current from battery 7, magnet 5, becomes deenergized and drops its armature 36, thereby closing at contact 37 the circuit of the test signal 45 which thereupon gives 5 notice of the inefficiency or inoperativeness of the system.

Inasmuch as armature 36 of magnet 5 vibrates between back contacts 35 and 47, on one side of the armature, and front stops 49 and 50 on the other side of the armature, 10 special provision is made to insure the closing of contacts 35 and 47 by the armature whenever the latter is released. Such provision is indicated in Fig. 2. In this figure, 15 the coils of magnet 5 are shown as supported by the base 51 on which are mounted bearings 52 and 53 to receive the rock shaft 54. Armature 36 is provided with a trunnion 55 turning in a bearing in the middle of the 20 shaft 54, said trunnion and rock shaft extending at a right angle to each other. As thus constructed, the armature is capable of 25 tilting on both of its pivotal supports and is sure to make a reliable electrical connection with both contacts 35 and 47, whether or not such contacts are accurately adjusted to the same distance from the poles of the 30 magnet or the stops 49 and 50. Armature 35 may be retracted against its back contacts 35 and 47 either by a spring or gravity. This special mounting of the armature is not herein claimed, it being the invention of another party and for which an application for a patent will be made.

The operation on the system is as follows: 35 When lever 33 of the signal transmitter is depressed and then released, signal wheel 31 rotates counter-clockwise. The first tooth lifts finger 30 and opens circuit controller 40 3. This breaks the signal circuit and deenergizes magnet 5 which thereupon releases its armature 36 to close contact 35, and thereby cut into the signal circuit said current-increasing circuit member and shunt 45 or cut out the high resistance circuit-portion. The first tooth of signal wheel 31 now passes finger 30, thereby permitting circuit controller 3 to close and complete the signal circuit. The high resistance circuit- 50 portion including high resistance magnet 5 and resistance 6 being now shunted from the signal circuit, the current in the signal circuit is greatly increased. Magnet 14 thereupon responds to the increase in current and 55 attracts its armature 23. Restoring magnet 4 also responds to this increase in current and attracts its armature but lags, in its action on its armature, somewhat behind the quicker action of magnet 14 on its armature. In the present instance, this is provided for by the longer travel required of armature 40 before it can lift armature 36, and the adjustment of its spring 42. As 60 armature 40 completes its movement toward magnet 4, finger 41 lifts armature 36 from

contact 35, thereby cutting out the current-increasing circuit member and again cutting in the high resistance circuit-portion. Magnet 4, thereupon, releases its armature 40 and magnet 14 also releases its armature 23, 70 the latter, on this return movement, causing one stroke to be given on gong 29, *i.e.*, the signal number 1. The circuit and the devices operated thereby are now in their normal condition but signal wheel 31 is 75 still rotating. When the next two teeth of signal wheel 31, which are relatively close together but spaced farther from the first tooth, act on finger 30, they cause, in the manner just described, two quick strokes to 80 be sounded on the gong 29, constituting the signal number 2. When the following three teeth, which are also relatively close together but spaced farther from the preceding two teeth, act on finger 30 they cause 85 three quick strokes to be sounded on the gong, thereby transmitting the signal number 3, and thus completing the signal 123.

It will be seen that in the system described, the signal circuit is normally closed with a current of minimum strength maintained in it during the long intervals of inactivity of the circuit and that, during such time as the system is actively in operation, the current strength is raised to and maintained at its maximum value during very short intervals of time. In fact, during the operation of the signal transmitter in the preferred arrangement as shown in the drawings, the maximum strength of the current is maintained in the signal circuit only during the moment after each tooth on the signal wheel 31 has passed finger 30 and before the consequent movement of armature 36 has been effected.

The invention is susceptible of various modifications. It is not essential to the invention that the signal circuit be raised from its minimum strength to its maximum strength and vice versa by varying its resistance, as is the case in the arrangements shown in Fig. 1. The current strength in the signal circuit may be varied by increasing and decreasing the current supply to the circuit, as by adding and subtracting battery power. Furthermore, restoring magnet 4, holding magnet 5 and signal instrument 1 need not all be, necessarily, normally included in series in the signal circuit, as is the case in Fig. 1. These devices or some of them may be included in separate circuits. These modifications are illustrated in Fig. 3. In the arrangement there shown, when the current increasing circuit member is included in the signal circuit, it adds an additional battery to increase the current in the signal circuit to its maximum. Moreover, the current-increasing circuit member is part of a normally closed circuit separate from the signal circuit and includes 130

restoring magnet 4, while magnet 5 and signal instrument 1 are included in the normally closed signal circuit, as in Fig. 1.

When the system is in active operation, magnet 4 and signal instrument 1 are momentarily included in series in the same closed circuit in which the maximum current, at the same time, is flowing from both batteries. In this arrangement, the battery is divided into two portions 7^a and 7^b. The normally closed signal circuit may be traced from battery 7^a, through wire 56, binding post 57, wire 58, magnet 5, wire 59, contact 50, armature 36, clip 61, wire 62, binding post 63, wire 64, circuit controller 3, wire 65, magnet 14 of sigr 1 instrument 1, and wire 66 back to battery 7^a. It will be noted that resistance 6 is omitted from this circuit, the resistance of magnet 5 being sufficient for the purpose in view of the reduced output of current from battery 7^a. Magnet 5 is energized and holds up its armature 36, as in Fig. 1. The current-increasing circuit member, including restoring magnet 4, may be traced from battery 7^b, through wire 67, magnet 4, wire 68, to clip 72 which is connected to contact 47. The rest of the closed circuit, of which this current-increasing circuit member is normally a part, may be traced onward from clip 72 through wire 68, coil 81 of instrument 69, resistance 70, wire 71, binding post 57 and wire 56 back to battery 7^b. Instrument 69, which may be a voltmeter, contains a circuit controller 73 which is held normally open by coil 81 and, when closed, acts to close the circuit of the test signal 45 as follows:—from battery 74, through wire 75, binding post 63, wire 62, wire 76, circuit controller 73, wire 78, and test signal 45 back to battery 74. If the circuit of magnet 4 and coil 81 is ruptured at any point or battery 7^b fails, coil 81 is deenergized, circuit controller 73 closes and test signal 45 gives the alarm. Contact 35 is connected by wire 79 with wire 78 so that if a rupture occurs at any point in the signal circuit or battery 7^a fails, thereby deenergizing magnet 5 and dropping armature 36, a similar alarm will be indicated by the test signal 45. In this case coil 81 is deenergized by the shunt established when armature 36 drops and connects wire 68 with wire 62 through clip 72, contact 41, armature 36 and clip 61 to wire 62, so that current from battery 7^b, which had previously been flowing through coil 81, now flows from the battery through wire 67, magnet 4, wire 68, clip 72, contact 47, armature 36, clip 61, wires 62 and 64, circuit controller 3, wire 65, magnet 14, wire 66 and battery 7^a to battery 7^b. Resistance 70, which is in the branch with coil 81 serves the purpose of cutting down the current through magnet 4 and coil 81 to the required amperage and may be ad-

justed to suit the requirements. When coil 81 is shunted, as just described, circuit controller 73 closes to complete the circuit through test signal 45 as follows:—from battery 74, through wires 75 and 62, clip 61, 70 armature 36, contact 35, wire 79, wire 78, and test signal 45 back to battery. Thus, the test signal 45 acts as a test both for the normally closed signal circuit and for the separate normally closed circuit which includes the current-increasing circuit member through magnet 4.

In the operation of the system shown in Fig. 3, when signal transmitter 2 is operated, the break at circuit controller 3 de-energizes magnet 5 which, thereupon, releases its armature. This cuts out the high resistance circuit portion which includes binding post 57, wire 58, magnet 5 and wire 59 to contact 50, by the break at contact 50 and connects into the signal circuit the current-increasing circuit member, which includes magnet 4, by closing the contact between armature 36 and contact 47, and this operation of the armature 36 at contacts 47 and 50 connects both batteries 7^a and 7^b in series with signal instrument 1 and magnet 4. The circuit now may be traced as follows:—from battery 7^b, through wire 67, magnet 4, wire 68, clip 72, contact 47, armature 36, clip 61, wire 62, wire 64, circuit controller 3, wire 65, signal instrument 1, wire 66, battery 7^a and wire 80 to battery 7^b. When, now, circuit controller 3 closes, magnet 14 attracts its armature 23 to strike the gong 29 and magnet 4 there-after operates to lift armature 36 to its normal position, whereupon magnet 14 releases its armature 23. It will be noted that in this case the gong 29 has been shifted so that it is struck on the front stroke of the armature, or when the circuit is closed at circuit controller 3 with the current at maximum, whereas, in Fig. 1, the gong is struck on the back stroke of the armature or when the circuit is broken at circuit controller 3.

It will be understood, of course, that in the signal instrument the armature 23, which in the drawings is shown as acting mechanically on the gong, may be arranged to act electrically to operate a local gong circuit, and that various changes in addition to those pointed out in the foregoing may be made without departing from the scope of the invention.

What I claim is:

1. The combination with a normally closed signaling circuit, of a source of electrical energy adapted in the normal condition of the circuit to supply a relatively small current; a signal instrument in the circuit responsive only to a relatively large current; a current changer operating to vary the current in said circuit and thereby operate the signal instrument; normally energized electromag-

netic means arranged when deenergized to operate the current changer; automatic means for restoring the current changer to normal condition after the sending of a signal, and a switch instrument controlling said electromagnetic means.

2. The combination with a normally closed signaling circuit, of a source of electrical energy adapted in the normal condition of 10 the circuit to supply a relatively small current thereto, a signal instrument in the circuit responsive only to a relatively large current, means including an electromagnetically actuated switching device for increasing the 15 current in the circuit, and electromagnetic means for automatically restoring the current changer to normal condition after the sending of a signal.

3. The combination with a normally closed 20 signaling circuit, of a source of electrical energy adapted in the normal condition of the circuit to supply a relatively small current; a signal instrument in the circuit responsive only to a relatively large current; 25 a current changer operating to vary the current in said circuit and thereby operate the signal instrument; electromagnetic means for operating the current changer comprising a high resistance magnet in the normally 30 closed signal circuit for holding the current changer in normal position and a low resistance restoring magnet for returning the current changer to normal position; and a switch instrument controlling said electro- 35 magnetic means.

4. The combination with a normally closed signaling circuit, of a source of electrical energy adapted in the normal condition of the circuit to supply a relatively small current; 40 a signal instrument in the circuit responsive only to a relatively large current; a current changer operating to vary the current in said circuit and thereby operate the signal instrument; electromagnetic means 45 for operating the current changer comprising a high resistance magnet for holding the current changer in normal position and a low resistance restoring magnet having a slow acting armature arranged to mechanically move the 50 current changer into normal position; and a switch instrument controlling said electromagnetic means.

5. The combination with a normally closed 55 signaling circuit, of a source of electrical energy adapted in the normal condition of the circuit to supply a relatively small current; a signal instrument in the circuit responsive only to a relatively large current; 60 a current changer operating to vary the current in said circuit and thereby operate the signal instrument; electromagnetic means normally on closed circuit for operating the current changer comprising a magnet in the normally closed signal circuit for holding 65 the current changer in normal position and

a restoring magnet for returning the current changer to normal position; and an automatically operating make-and-break signal transmitter in the signal circuit and controlling said electromagnetic means.

6. The combination with a normally closed signaling circuit, of a source of electrical energy adapted in the normal condition of the circuit to supply a relatively small current; 70 a signal instrument in the circuit responsive only to a relatively large current; a current changer operating to vary the current in said circuit and thereby operate the signal instrument; electromagnetic means normally on closed circuit for operating the current changer comprising a high resistance magnet for holding the current changer in normal position and a low resistance restoring magnet having a slow acting armature arranged to mechanically move the 75 current changer into normal position; and a switch instrument controlling said electromagnetic means.

7. The combination with a signaling circuit normally including a high resistance 80 circuit-portion; a signal instrument and a signal transmitter connected with the circuit beyond said high resistance circuit-portion; a current-increasing circuit member; a circuit controller operating to cut out of the 85 signal circuit said high resistance circuit-portion and cut into said signal circuit said current-increasing circuit member and vice versa; a holding magnet in said high resistance circuit-portion normally energized to 90 hold said circuit controller in normal position to cut out of the signal circuit the current-increasing circuit member and cut into said signal circuit the high resistance circuit-portion; a magnet responsive when the 95 current-increasing circuit member is cut into the signal circuit and acting to move the circuit controller back to normal position.

8. The combination with a signaling circuit normally including a high resistance 100 circuit-portion; a signal instrument and a signal transmitter connected with the circuit beyond said high resistance circuit-portion; a current-increasing circuit member; a circuit controller operating to cut out of the 105 signal circuit said high resistance circuit-portion and cut into said signal circuit said current-increasing circuit member and vice versa; a magnet controlling the movement of the circuit controller in one direction; 110 and a magnet controlling the movement of the circuit controller in the other direction.

9. The combination with a signaling circuit normally including a high resistance 115 circuit-portion; a signal instrument and a signal transmitter connected with the circuit beyond said high resistance circuit-portion; a current-increasing circuit member; a circuit controller operating to cut out of the 120 signal circuit said high resistance circuit-portion and cut into said signal circuit said high resistance circuit-portion.

portion and cut into said signal circuit said current-increasing circuit member and vice versa; a magnet controlling the movement of the circuit controller in one direction; and a magnet controlling the movement of the circuit controller in the other direction; said latter magnet being responsive when the current-increasing circuit member is cut into the signal circuit.

10 10. The combination with a normally closed signaling circuit; a normally inactive signal instrument in said circuit; a current changer operating to vary the current in said circuit and thereby operate the signal instrument; a normally energized holding magnet for said current changer; and a normally unresponsive restoring magnet operating to restore the current changer to normal position after it has been released by the holding magnet.

15

20

11. The combination with a normally closed signaling circuit; a normally inactive signal instrument in said circuit; a current changer operating to vary the current in said circuit and thereby operate the signal instrument; a normally energized holding magnet for said current changer; and a slow-acting normally unresponsive restoring magnet operating mechanically to restore the current changer after it has been released by the holding magnet.

12. The combination with a normally closed signalling circuit, of a source of electrical energy adapted in the normal condition of the circuit to supply a relatively small current; a signal instrument in the circuit responsive only to a relatively large current; a current changer operating to vary the current in said circuit and thereby operate the signal instrument; electromagnetic means for operating the current changer comprising a holding magnet for holding the current changer in normal position and a restoring magnet for returning the current changer to normal position; a switch instrument controlling said electromagnetic means; and a test signal controlled by said holding magnet.

13. The combination with a normally closed signaling circuit, of a source of electrical energy adapted in the normal condition of the circuit to supply a relatively small current thereto; a signal instrument in the circuit responsive only to a relatively large current, means including an electromagnetically actuated switching device for increasing the current in the circuit, automatic means for restoring the current changer to normal condition after the sending of a signal, and a test signal controlled by said switching device.

14. The combination with a signaling circuit normally including a high resistance circuit-portion; a signal instrument and a
65 signal transmitter connected with the cir-

cuit beyond said high resistance circuit-portion; a current-increasing circuit member; a circuit-controller operating to cut out of the signal circuit said high resistance circuit-portion and cut into said signal circuit said current-increasing circuit member and vice versa; a holding magnet normally energized to hold said circuit controller in normal position to cut out of the signal circuit the current-increasing circuit member and cut into said signal circuit the high resistance circuit-portion; a magnet responsive when the current-increasing circuit member is cut into the signal circuit and acting to move the circuit controller back to normal position; and a test signal arranged to operate when the normal current in the signal circuit is interrupted.

15. The combination with a normally closed signaling circuit, of a source of electrical energy adapted in the normal condition of the circuit to supply a relatively small current; an audible signal instrument in the circuit responsive only to a relatively large current; a current changer operating to vary the current in said circuit and thereby operate the signal instrument; automatic means for restoring the current changer to normal condition after the sending of a signal; and a signal transmitter controlling said current changer and adapted to send at each operation a group of signal impulses of relatively large current over the signal circuit to cause the signal instrument to respond to each impulse of the group. 100

16. The combination with a normally closed signaling circuit, of a source of electrical energy adapted in the normal condition of the circuit to supply a relatively small current; a signal instrument in the circuit responsive only to a relatively large current; a current changer operating to vary the current in said circuit and thereby operate the signal instrument; electromagnetic means for operating the current changer comprising a magnet for holding the current changer in normal position and a restoring magnet for returning the current changer to normal position; and a signal transmitter adapted to send a group of current impulses into the signal circuit and thereby cause the signal instrument to respond in accordance with said impulses. 105 110 115

17. The combination with a signaling circuit including an audible signal instrument, 120 said circuit normally including a high resistance circuit-portion; a current-increasing circuit member; a circuit controller operating to cut out of the signal circuit said high resistance circuit-portion and cut into said signal circuit said current-increasing circuit member and vice versa, a holding magnet in said high resistance circuit-portion normally energized to hold said circuit controller in normal position to cut out of the signal circuit 134

cuit the current-increasing circuit member and cut into said signal circuit the high resistance circuit-portion; a magnet responsive when the current-increasing circuit member is cut into the signal circuit and acting to move the circuit controller back to normal position; and a signal transmitter adapted to send a group of current impulses into the signal circuit and thereby cause the signal

instrument to respond in accordance with 10 said impulses.

This specification signed and witnessed this 24th day of January, A. D. 1913.

RICHARD M. HOPKINS.
